UNITED STATES PATENT OFFICE.

HENRI EUGÈNE DÉSIRÉ COGÉRY AND CLAUDE FRANÇOIS BENOIT GEORGES BERTRAND,
OF PARIS, FRANCE.

LOOSE-LEAF BINDER.

Application filed August 28, 1926, Serial No. 132,154, and in Belgium August 31, 1925.

This invention relates to binders of the kind generally called "loose leaf binders", and has for its object so to construct devices of the class in question which are furnished with locking means for locking the binder with the leaves in position, that such locking means while being equally effective to the means usually employed are more simple in construction and consequently more economical.

The binders of the kind to be considered are provided with two strips or elongated plates, between which the edges of the loose leaves to be bound are held fast. The two strips are held relatively to one another, by turning over two specially constructed fastening devices upon one of the strips, such devices being connected to the other strip. In the usual constructions, the fastening devices consist of two rods or pins, each formed in two portions with the upper portion hinged to the lower. These hinged pins are passed through perforations or the like in the upper strip and then turned down over such strip, and means are added for retaining the upper hinged portion thus turned down position.

The present invention refers essentially to the improved means for locking or holding in position the ends of the pins when thus turned down, the locking device being constituted by an element hinged to the extremity of the pin and adapted to engage with suitable corresponding devices at the extremity of the plate.

The invention also refers to certain constructional embodiments which will be more fully described hereafter.

In order that the invention may be clearly understood, it will now be explained with reference to the accompanying drawings, but it is to be observed that the description and drawings are given merely by way of example.

Fig. 1 of these drawings shows in perspective, a loose leaf binder constructed according to the invention.

Fig. 2 shows in vertical longitudinal section, one of the ends of the said binder.

Fig. 3 shows in vertical section on 3—3, Fig. 2, certain details of the binder.

Fig. 4 shows in plan the parts of the binder shown in Fig. 3.

Fig. 5 shows, to a larger scale, but in the same manner as Fig. 2, certain parts of the

binder illustrated in the right hand upper portion of Fig. 2.

As regards the details of the binder itself, with the exception of the special locking means to be combined therewith, these are of a character already known.

In the construction illustrated they comprise two plates *a* or strips, parallel to one another and interconnected by rods or pins, which engage the edges of the movable sheets *b* to be bound. There are two series of these pins, one of the series *c* comprises a pair of pins, adjustable as to height and extending from one plate to the other. The second series of pins comprises a pair, each of which is formed in two parts hinged together at *d*. One of the parts *e* is fixed to the bottom plate or strip, and the other part *f* is adapted when the two strips are fitted together and at the desired distance apart from one another, to be turned down and over longitudinally upon the outer surface of the upper plate, into a groove *g* provided therein for the purpose. This groove is open at the end, and when the hinged portion *f* has been turned down its extremity comes in alignment with the corresponding extremity of the upper plate. The said part *e* can have its height adjusted by constructing it like one of the members *c*.

Referring now to the locking system to be combined with the binder and constituting the essential feature of the invention, this is constituted by hinging to the extremity of the part *f* of each pin a small device *h*. This device may be constructed in various ways, but in the example shown it is formed from two stamped shells attached together edge to edge and having two rivets *i* passing therethrough. It is connected to the pin *f* by resilient means. The means in the example shown consists of wire hooks, which are attached to the rivets *i* and pass out through recesses in the shells and into a hole at the extremity of the pin *f*.

At the end of the groove *g*, two curved recesses *k* are provided, which are clearly visible at Fig. 4. Between them is formed a sort of tongue *l*, fashioned from the metal of the upper plate *a* and having a slightly curved portion, seen clearly at Fig. 5.

The whole device, including the stamped portions *h*, the wire hooks *j*, the recesses *k* and the tongue *l* are so made and co-operate that when the pin *f* is turned down into the

groove *g* and the device *h* turned down on its hinge, the wires *j* engage in the recesses *k*, after separating to allow for the passage of an enlargement on the tongue *l*. The wires *j* then come to the bottom of the recesses *k*, and the locking is complete, the device *h* in the completely turned down position being also retained from turning by the curving of the piece *l*, of tongue-like formation.

As previously stated, the invention is not limited in any way to the particular construction of the locking device illustrated, all modifications being included falling within a fair interpretation of the claims.

What we claim and desire to secure by Letters Patent of the United States of America is:—

1. A loose leaf binder comprising a first cover member, a second cover member, a pin connected to said first cover member and extending into the second cover member, a pin pivotally connected to the first mentioned pin and overlying the second cover member, the second cover member having a tongue at the edge thereof and located adjacent the free end of the pivoted pin, and a locking
- 20
- 25

element embodying resilient means connected to the free end of the said pivoted pin, the said locking element being adapted to detachably engage the said tongue.

2. A loose leaf binder comprising a first cover member, a second cover member, a pin connected to said first cover member and extending into the second cover member, a pin pivotally connected to the first mentioned pin and overlying the second cover member, the said cover member having a tongue formed in the edge thereof, the said tongue having an enlarged head of tapering contour and a locking element connected to the free edge of the said pivoted pin by resilient wire means, the said resilient wire means being adapted to yield sufficiently to pass behind the enlarged head of the tongue.

3. A device according to claim 2 in which the said resilient wire means are pivotally engaged to the free edge of the pivoted pin.

In testimony whereof we hereunto affixed our signatures.

HENRI EUGÈNE DÉSIRÉ COGÉRY.
CLAUDE FRANÇOIS BENOIT GEORGES BERTRAND.
